UNITED STATES PATENT OFFICE

163,913

AIRPLANE

John W. Thorp, Burbank, Calif., assignor to Fletcher Aviation Corp., Pasadena, Calif., a corporation of California

Application April 3, 1950, Serial No. 8,940

Term of patent 14 years

(Cl. D71—1)

To all whom it may concern:

Be it known that I, John W. Thorp, a citizen of the United States, residing at Burbank in the county of Los Angeles, and State of California, have invented a new, original, and ornamental Design for Airplane, of which the following is a specification, reference being had to the accompanying drawing, forming part thereof, in which:

Fig. 1 is a side elevational view of an airplane showing my new design;

Fig. 2 is a front elevational view wherein the propeller has been omitted for convenience of illustration;

Fig. 3 is a top plan view thereof.

Fig. 4 is a perspective view of the plane.

I claim:

The ornamental design for an airplane, substantially as shown.

JOHN W. THORP.
